PUMPING WELL SHUT-OFF VALVE

Wilbur L. Dunn, 1204 E. 25th 74114, and Paul H. Johnson, 4259 E. 71st Place 74135, both of Tulsa, Okla.

Filed Oct. 22, 1965, Ser. No. 501,219
6 Claims. (Cl. 200—82)

This invention relates to a pumping well shut-off valve. More particularly, the invention relates to a valve adapted to be placed in the flow line of a pumping oil well to detect the cessation of fluid flow and to actuate a switch to shut the well off upon the cessation of fluid flow.

Most oil wells, after an initial period in which the underground pressure is sufficient to force the produced fluid to the surface, undergo an extended period during which the crude must be pumped to the surface. The most common methods of pumping wells is the use of a bottom hole positive displacement pump reciprocated by a string of sucker rods. These types of pumps produce a pulsating fluid flow at the surface. Most pumping equipment is designed to pump somewhat in excess of production rate so that the wells are pumped only part time, that is, by timed cycles. For instance, some wells are pumped for one period a day while others may be pumped for two or three periods during the day. A most common method of controlling the pumping cycles is by the use of time clocks which turn the well pumping system on and off at preselected periods. With use of such time clocks the actual pumping time must be estimated and frequently it is impossible to accurately predict the exact amount of time which will be required for pumping a well. Wells are frequently timed to pump slightly longer than the estimated maximum time required to insure maximum production. This means that with each pumping cycle the well so timed will pump for a period after the production of crude oil has ceased. The pumping of wells after production ceases is expensive in that unnecessary wear on the pumping equipment occurs. In addition, the power costs of producing a well increases and the polish rod is not bathed in the produced crude and therefore runs dry, tending to wear out the polish rod stuffing box.

This invention provides a means of detecting the cessation of fluid flow in a pumped oil well and of actuating a switch to shut off the pumping system when fluid flow ceases.

This basic object and more particular objects will be understood from the following description and claims taken in conjunction with the attached drawings in which:

FIGURE 1 is an external view of the pumping well shut off valve of this invention.

FIGURE 2 is an enlarged cross-sectional view of the shut off valve of this invention.

FIGURE 3 is a partial enlarged cross-sectional view of the valve showing the plug raised slightly by the effect of gas pressure and showing the method by which gas is vented by the valve.

FIGURE 4 is a cross-sectional view as in FIGURE 3 but showing the valve plug raised by fluid pressure to the point where fluid flow through the valve occurs.

FIGURE 5 is a segmented view showing an alternate arrangement of the invention utilizing a diaphragm as a means of sealing the valve stem.

FIGURE 6 is a segmental cross-sectional view showing an alternate arrangement of the upper end of the valve stem of the valve of this invention providing an overtravel means for actuating the switch.

FIGURE 7 is a cross-sectional view taken along the line 7—7 of FIGURE 6.

Referring now to the drawings and first to FIGURE 1, the pumping well shut-off valve of this invention is in-

2

dicated by the numeral 10 and is shown positioned in an oil well lead line 12 through which crude oil produced by the well flows.

Referring to FIGURE 2, the valve is shown in enlarged cross-sectional view. The valve includes a body 14 having a flow passageway 16 therethrough. A portion of the flow passageway 16 includes a vertical cylindrical flow chamber 18. At the top of the flow chamber 18 is provided a horizontal sealing surface 20.

The body 14 has an upper opening 22 which is closed with a bonnet 24. The bonnet in turn has an opening 26 which is closed with a stem guide 28 having a vertical stem opening 30.

Positioned in the vertical flow chamber 18 is a valve plug, generally indicated by the numeral 32, which includes a vertical cylindrical portion 34 and an upper larger diameter horizontal flange portion 36. Beneath the flange portion 36 is a flat sealing gasket 38 which may be optionally utilized to seal again fluid flow in the reverse direction through the valve. Downwardly extending from the vertical cylindrical portion 34 are integral guide fingers 40 which provide flow passageways 42 therebetween.

The valve plug 32 is affixed to an axial valve stem 44 which extends upwardly and is slidably and sealably received by stem opening 30. A gasket 46 prevents leakage of fluid at the stem opening 30.

The valve plug 32 is provided with a small diameter gas opening 48 for purposes to be described subsequently. The gas opening 48 is in the cylindrical portion of the valve plug 34 and communicates with the exterior of the cylindrical portion adjacent to and below the integral horizontal flange portion 36, or when the sealing gasket 38 is provided, below such sealing gasket.

Supported to valve bonnet 24 above the valve is a switch member 50 which preferably is contained in a housing 52. The switch member 50 has a downwardly extending actuating element 54. Switch member 50 is of a type commercially available providing an electrical contact when actuating element 54 is depressed and a pneumatic time delay of switch of deactivation. The amount of time delay is controlled by knob 56.

A plate 58 is supported above valve body 14 by bolts 60, the plate having an opening 62. A stem extension 64 passes through the opening 62, the stem extension having a bolt 68 axially extending from the upper end thereof. A tubular guide 70 having a flange 72 reciprocally receives the stem extension 64. At the juncture of the stem extension 64 and the valve stem 44 a spring retaining washer 74 is provided. Between the guide flange 72 and the spring washer 74 a spring 76 is inserted, the spring being in compression to normally urge the valve stem 44 and thereby the valve plug 32 downwardly into sealing engagement with the valve body.

When the well to which the valve of this invention is applied is pumping and a surge of produced fluid flows through the lead line 12, the fluid flow will force the valve plug 32 upwardly. Fluid cannot pass through the valve until the plug 32 is moved upwardly the height required for the plug cylindrical portion 34 to clear the vertical flow chamber 18. This position is shown in FIGURE 4. With the cylindrical portion 34 above the flow chamber 18 fluid flow can pass through the guide fingers 40. This upward movement of the valve plug 32 and stem 44 causes the bolt 68 to engage switch plunger 54 and actuate the switch.

In some oil wells gas is produced even though no fluid is being produced. In most instances it is not economically desirable to pump an oil well after fluid flow has ceased even though some gas flow continues. If the gas pressure builds sufficiently to cause the plunger 32 to move

upwardly a false indication of fluid flow would be given. To correct for this situation a unique feature of this invention is the provision of the previously mentioned small diameter gas opening 48 in the cylindrical portion 34 of the valve plug. The effect on the valve of gas pressure is shown in FIGURE 3. The gas pressure will force the plug 32 upwardly so that the small diameter gas opening 48 clears the top of the vertical flow chamber 18. This permits the gas to vent but in a manner such that the valve plug 32 is not moved upwardly sufficient to actuate the switch. Thus, the gas pressure vented through the valve without giving a false indication of fluid flow.

In the arrangement of FIGURE 2 the valve stem 44 is sealed by a gasket 46. An alternate arrangement of sealing the stem is shown in FIGURE 5. In this arrangement the valve stem 44 is formed of lower portion 44A and upper portion 44B and between the portions the center of a diaphragm 78 is positioned. The outer circumference 80 of the diaphragm 78 is sealed against the bonnet 24 by means of a washer 82 having a large diameter opening 84 therein. The washer is held against the valve bonnet 24 by means of spaced bolts 86. In the arrangement of FIGURE 5 the valve stem 44 rises and falls as actuated by the plug 32, the diaphragm 78 permitting such reciprocation without leakage.

FIGURES 6 and 7 show an alternate arrangement providing an adjustable over-travel means for the actuation of switch 50. Bolt 68 is provided with an axial opening 88 which slidably receives a guide pin 90. A spring 92 urges the guide pin 90 upwardly. To strain the upward travel of the guide pin 30 bracket 94 extends from the guide pin head downwardly and is turned under the head of bolt 68. In this arrangement when the valve stem extension 64 is moved upwardly by flow in the valve the guide pin 90 contacts the switch actuating element 54 to actuate the switch. If unusually large fluid flow occurs in the valve moving the plug upwardly more than the normal travel, the over-travel is compensated for by the spring 92.

By means of this invention the flow of fluid from a pumped oil well is detected by switch 50 which, being of the time delay type, is adjusted so that the pulsating fluid flow continues to maintain the switch in actuated condition. Upon cessation of the pulsating fluid flow the switch deactuates to shut off the pumping well.

The invention provides a valve for detecting pulsating fluid flow in an arrangement wherein gas pressure is vented through the valve without a false indication of fluid flow.

While the invention has been described with a certain degree of particularity it is manifest that many changes may be made in the details of construction and the arrangement of components without departing from the spirit and scope of this disclosure.

What is claimed:

1. A pumping well shut-off valve comprising:
a body having a flow passageway therethrough, a

portion of said flow passageway defined by a vertical cylindrical flow chamber, the body having a horizontal sealing surface around and above the flow chamber and a vertical stem opening therein in axial alignment with said cylindrical flow chamber;

a valve plug having a vertical cylindrical portion slidably received in said cylindrical flow chamber and an upper larger diameter integral horizontal flange portion, the cylindrical portion having lower spaced integral downwardly extending guide fingers, the guide fingers providing flow passageways therebetween, the valve plug having a small diameter gas opening in the cylindrical portion, the opening communicating with the exterior of the cylindrical portion adjacent to and below the integral horizontal flange portion;

an axial stem affixed at the lower end to said valve plug and extending slidably and sealably through said body vertical stem opening; and

a switch member supported to and above the valve body, the switch member having an actuating element extending therefrom aligned to engage the upper end of said stem whereby the switch member is actuated by fluid flow through the valve body.

2. A pumping well shut-off valve according to claim 1 including a sealing gasket affixed to the lower surface of said valve horizontal flange portion for engaging the said horizontal sealing surface, said gas opening communicating with the exterior of said valve plug cylindrical portion adjacent to and below the sealing gasket.

3. A pumping well shut-off valve according to claim 1 including spring means biasing the valve plug downwardly.

4. A pumping well shut-off valve according to claim 1 wherein the upper end of said stem has an axial threaded opening therein and including a bolt threaded into said stem opening providing means of adjusting the actuation of said switch member.

5. A pumping well shut-off valve according to claim 1 including adjustable spring biased over-travel means affixed to the upper end of said stem for engagement of said switch.

6. A pumping well shut-off valve according to claim 1 including a sealing diaphragm having an axial opening therein sealably received by said stem, the outer diameter of said diaphragm received by said body.
